DESIGN FOR A BUTTON COVER

Harry Broder, New York, N. Y.

Application January 14, 1937, Serial No. 67,048

Term of patent 3½ years

To all whom it may concern:

Be it known that I, Harry Broder, a citizen of the United States and a resident of the city and State of New York, with a post office address at No. 161 West 54th Street, in the Borough of Manhattan, city and State of New York, have invented a new, original, and ornamental Design for Button Covers, of which the following is a specification, reference being had to the accompanying drawing, forming part thereof in which:

I claim:

The ornamental design for a button cover, as shown and described.

HARRY BRODER.
